UNITED STATES PATENT OFFICE.

GEORG KIRKEGAARD, OF NEW YORK, N. Y.

BOTTLE-STOPPER.

No. 874,685.

Specification of Letters Patent.

Patented Dec. 24, 1907.

Application filed October 5, 1905. Serial No. 337,507.

To all whom it may concern:

Be it known that I, GEORG KIRKEGAARD, a citizen of the United States, and a resident of the city of New York, in the county of New York and State of New York, United States of America, have invented certain new and useful Improvements in Bottle-Stoppers, of which the following is a specification.

My invention relates to an improvement 10 on a bottle stopper which I have invented and for which Letters Patent of the United States, No. 829,341, were issued to me on the 21st day of August, 1906.

The present invention relates to an improvement 15 which I have made in connection with this stopper for the purpose of preventing the reuse of the stopper after it has been once removed from the bottle.

I will describe my invention in the following 20 specification and point out the novel features thereof in claims.

Referring to the drawings, Figure 1 is a perspective view of my improved bottle stopper. Fig. 2 is a side elevation of the same. Fig. 3 is a section of the upper part of a bottle with one of my stoppers applied thereto. Fig. 4 is a sectional view of a cap, the section being taken through the line X—X of Fig. 3 and the view being taken in the direction of 30 the arrows. Fig. 5 is a blank from which the cap is formed.

Like characters of reference designate corresponding parts in all of the figures.

10 designates a cap which is constructed 35 of sheet metal such, for example, as tin. The metal is first stamped out into a blank of a form substantially like that illustrated in Fig. 5. The bottle stopper comprises a disk portion 11 which has an annular depending 40 flange 12. These together form an inverted cup within which is placed a packing disk 13 of cork or other suitable material. At three points around the periphery of the disk and at substantially equal distances apart are 45 formed fingers 20, one of these being extended, as shown at 21, to form a handle or tail-piece.

The fingers are embossed or pressed in a manner and for the purpose fully set forth in Letters Patent No. 829,341 so that each of 50 them has a hollow lug 22, which is arranged to engage with the inclined shoulder 31 around the neck of the bottle 30 to which the stopper is to be applied, and stiffening ribs 23 which extend from points over the edge of 55 disk 11 downward and below the holding lugs

22. Between the ribs the metal of the flange 12 is bulged outward above the projecting lug 22 as indicated at 24 so that the whole structure of the finger is far more rigid and strong than the remaining portions of the 60 flange and disk. The flat portion designated by 25 is provided for the purpose of accomplishing the operation of applying the cap to a bottle by means of a die or other tool which may be arranged with cam-surfaces 65 which come in contact with these surfaces 25 for this purpose and thus the flattening out and destroying the function of the stiffening ribs 23 by this operation is avoided.

In applying this stopper to a bottle or jar 70 a die or other tool is used for pressing the disk down upon the mouth of the bottle so as to compress the packing material 13 and then pressing the lower portion of the fingers 20 into engagement with the annular shoulder 31 of the bottle. The cap thus secured to the bottle is held firmly in place by the strength of the fingers and it is capable of 75 withstanding considerable pressure from the inside of the bottle. 80

The structure thus far described is more fully set forth in the aforesaid Letters Patent. It is capable of being replaced upon a bottle from which it has been removed. I find, however, that it is sometimes desirable 85 to prevent the resealing of a bottle by its original stopper and the purpose of the present invention is to so construct the cap that the operation of removing it from the bottle will so destroy it that it cannot be effectively 90 used again. To this end I provide on either side of the finger 20, on which is the handle or tail-piece 21, grooves 26, 26 indented or scratched into the inner surface of the depending flange 12. In the operation of 95 stamping these caps it is desirable to form these grooves after the flange has been bent into its shape. The grooves are slightly indented into the surface of the metal and are not deep enough to destroy the strength of 100 the fingers.

After the cap has been attached to a bottle as above described and when it is desired to remove it from the bottle this may be readily done by grasping the lower end of the handle 105 or tail-piece 21, which is provided for this purpose, and forcing the latter outward and upward. The peculiar construction of the finger which carries the tail-piece 21 is such that its rigidity and strength are much 110

greater than that of the flange 12 through which it passes. The grooves or indentations 26 further weaken the flange at either side of this finger so that the pressure necessary to remove the cap will cause the fibers of the flange to be broken at these points so that the flange will be broken through at these two points or else will be so much weakened that this particular finger cannot be used again to hold the cap onto a bottle; consequently, it may be seen that the usefulness of the cap is destroyed by the operation of removing it from the bottle.

What I claim is.—

1. A bottle stopper comprising a metallic cap containing a packing material and having a number of depending fingers around its periphery, a handle or tail-piece extending from one of the fingers, each finger having an inwardly extending lug for engaging the neck of a bottle and stiffening ribs surrounding said lugs and extending upward to the top of the cap; the inner surface of the flange being provided with fracture grooves parallel to the fingers, one of said grooves being on

either side of the finger from which the handle extends.

2. A bottle stopper comprising a sheet metal cap containing packing material and having a depending flange, fingers extending from the lower edge of said flange and provided with a reinforcement extending 30 from their lower ends upward through the width or depth of the flange, one of said fingers having a handle or tail-piece provided with a 35 reinforcement extending through its handle and continuing through the length of the finger to which it is attached and the width of the flange, the inner surface of the flange being provided with fracture grooves, one of 40 said grooves being on each side of the finger from which the handle extends.

In testimony whereof I have signed my name to this specification in the presence of two subscribing witnesses.

GEORG KIRKEGAARD.
